FUSE HOLDER

Robert L. Smythe and Alwin G. Steinmayer,
Milwaukee, Wis., assignors to Line Material
Company, South Milwaukee, Wis., a corpora-
tion of Delaware

Application April 11, 1932, Serial No. 604,426

5 Claims. (Cl. 200—134)

This invention relates to fuse holders, and although it may be used with different types of fuses, it is particularly applicable to holders for liquid fuses.

- 5 This invention provides a novel form of holder which obtains a very secure grip upon the two contacts of the fuse and thus mechanically holds the fuse in place in a very secure manner, and in addition to this secures a very firm contact 10 pressure and a very extensive face to face contact between the terminal portions of the holder and the contacts of the fuse, thus securing an excellent electrical connection with the terminal contacts of the fuse.
- 15 Further objects are to provide a fuse holder which is so made that the fuse may be readily inserted in the holder and a pressure applying means operated to thereafter secure a relatively high contact pressure between the terminals or 20 contact members of the holder and the terminals or contact members of the fuse, the apparatus being so made that this pressure may be readily relieved to permit the easy removal or replacement 25 of the fuse, a certain amount of spring pressure being maintained at all times to prevent the inadvertent dropping of the fuse from the holder during the period of insertion or removal.

Further objects are to provide a construction which is very simple, which is inexpensive to 30 make, and which is easy to operate.

Embodiments of the invention are shown in the accompanying drawings, in which:—

Figure 1 is a side elevation, with parts in section, showing a fuse in position in the holder.

35 Figure 2 is a sectional view on the line 2—2 of Figure 1.

Figure 3 is a view corresponding to Figure 2, with parts in section, showing a further form of the invention.

40 Figure 4 is a sectional view on the line 4—4 of Figure 3.

Figure 5 is a fragmentary view showing a further form of the invention.

Figure 6 is a side elevation of the structure 45 shown in Figure 5.

Figure 7 is a fragmentary view showing a further form of the invention.

Figure 8 is a side elevation of the structure shown in Figure 7.

50 Figure 9 is a fragmentary view of a further form of the invention.

Figure 10 is a fragmentary view of a further form of the invention.

55 Referring to the drawings, particularly Figures 1 and 2, it will be seen that the fuse holder

comprises a channel-shaped metal base member 1 upon which are mounted the outwardly projecting insulators 2 and 3. These insulators carry the terminal plates or members 4 and 5.

The upper and lower clamping members may 5 be of substantially identical construction if desired, or may be slightly different, as has been indicated in Figure 1.

Each of the clamping members comprises a pair of spring jaws or contact members 6 which 10 are preferably integrally joined by the yoke portion 7. These jaws are also advantageously pro-

vided with outwardly turned guiding lips 8 to facilitate the insertion of the terminal portions or 15 contacts of the fuse. The terminal portions or contacts of the fuse are indicated at 9 and 10 in Figure 1, and each contact portion or terminal portion is provided with a flat face respectively indicated at 11 and 12. These flat faces

are placed in face to face contact with the opposed faces of the spring jaws 6. It is also prefer- 20 able to provide a small protuberance 13 or

bulge upon each spring jaw 6 to aid in retaining the fuse in position immediately after insertion and prior to the application of the clamping 25

pressure thereto. Also there is a sort of snap 30 action as the fuse is pressed into place, as will be readily appreciated, so that there is a tendency to insure pushing of the fuse all the way into place during insertion. Further, these pro-

35 tuberances 13 afford a slight additional security against displacement of the fuse after it is clamped in place.

A pressure member carrying yoke is provided 35 and may consist of a pair of upwardly extending arms 14 located on opposite sides of the contact arms 6, see Figure 2.

This yoke or bracket member is formed of relatively heavy sheet metal and preferably formed as one integral structure, although obviously this 40 identical construction could be varied, as desired. This yoke member or bracket member is provided with inwardly turned feet or supporting portions 15 and these portions are clamped in

place against the terminal member or plate 4 by 45 means of screws 16, such screws passing through the yoke 7 of the contact members or spring arms 6, as clearly shown in Figure 2.

It is also preferable to provide an apron portion 17 integral with the arms 14 and arched 50 inwardly, as indicated at 18, to aid in correctly

positioning the fuse and also to give strength to the structure. This apron portion is preferably provided with an indentation or inwardly pressed 55 portion 19 which is located directly rearwardly

of the terminals or contacts 9 and 10 of the fuse to thus provide a stop against which these contacts 9 and 10 may bear to correctly position the fuse with reference to the arms 6.

5 A short screw member or pressure applying member 20 is threaded through each of the arms 14 and is provided with a bearing head 21 preferably swiveled to the shank portion and engaging the corresponding spring arms 6. These pressure applying members or screws 20 are reversely threaded and are simultaneously operated by means of a bail or operating member 22. A simple construction is to form this operating member 22 of relatively stiff wire or rod bent, as shown in Figures 1 and 2, and to pass the ends thereof through transverse apertures in the shanks 20 and to slightly rivet or swell the extreme ends of the bail as indicated at 23 in Figure 1.

Also, if desired, the bail 22 may be so bent that it is arrested in final clamping position by the outwardly turned guiding lips 8 of the arms 6, although this is not wholly necessary, as the motion of the bail is arrested when suitable clamping pressure is obtained, as will be immediately appreciated,

It is preferable, however, to so adjust the apparatus that the fuse is locked in place with a very firm contact pressure when the bails 22 stand in about the position shown in Figure 1. They, therefore, form loops approximately around the ends of the fuse when in this position, but do not approach each other and therefore do not lessen the gap between the terminals of the fuse.

35 When it is desired to relieve the pressure, it is merely necessary to rock the bails 22 in opposite directions, as indicated by the arrows in Figure 1, the shanks 20 of the pressure applying members being suitably threaded to permit this mode of operation.

The lower clamping member is substantially identical with the upper clamping member. However, it may be desirable to provide a rest plate or bottom plate 24, see Figures 1 and 2, 45 which assists in the positioning of the fuse, and in addition offers additional support against downward motion of the fuse during the blowing thereof. Obviously the plate 24 may have its outer portion slightly downturned or bevelled, as 50 shown in Figure 1, to further facilitate insertion of the fuse.

Before describing the several forms of this invention it is to be noted particularly that the bottom plate 24 may be employed or may be omitted with any form of the invention.

Referring to the form shown in Figures 3 and 4, it will be seen that substantially the same principle is employed. In this form of the invention, however, the yoke member 25 is preferably channel-shaped and provided with an apron 26 on each side. This, of course, gives additional rigidity and this structure may be formed of sheet metal, as in the first form of the invention, or may be cast if desired. Obviously the same practice 60 could be followed with reference to the first form of the invention described hereinabove.

In this latter form of the invention shown in Figures 3 and 4 the clamping arms are indicated by the reference character 27 and are operated by means of the bail or operating member 28 through the medium of the threaded shanks 29 provided with the swiveled bearing heads 30, all as previously described. A slightly different bottom supporting plate 31 has been shown, although this, of course, may be varied as required.

In the form of the invention shown in Figures 5 and 6 a single shaft 32 extends completely through the device and receives the end of the manipulating bail 33. Its ends are reversely threaded through the pressure applying members 34. These members 34 are provided with inwardly turned ends 35 which bear against the spring arms 36. The inner ends of the members 34 are apertured and receive the projecting nibs or ears 37 of the bar or member 38, such latter member and the yoke 39 of the spring arms 36 being secured to the plate 5 as shown.

5 In the operation of this form of the invention it is apparent that when the shaft or pressure applying member 32 is rotated in the proper direction, the members 34 will rock about the shoulders 40 of the bar 38 and their inturned ends 35 will press the arms 36 towards each other, thus applying the requisite pressure to the contacts of the fuse.

10 In the form of the invention shown in Figures 7 and 8 substantially the same construction as that described in connection with Figures 5 and 6 is employed. However, the spring arms 41 are provided with slots or notches at their outer ends 20 through which extensions 42 formed integrally with the members 43 are passed. The extensions 42 are provided with inwardly directed portions which move inwardly beyond the outline of the contacts of the fuse and thus prevent the removal of the fuse, even if force sufficient to overcome the frictional pressure is applied to the fuse. However, it is to be noted that in all forms 30 of the invention the bails somewhat guard against the complete removal of the fuse, even if force 35 sufficient to overcome the frictional contact was imparted to the fuse, as the bails somewhat overlap the ends of the fuse.

25 Returning to Figures 7 and 8, it will be seen that the members 43 are pivoted upon the bar 38 in a manner identically similar to that described in connection with Figures 5 and 6. The members 43 are provided with inwardly turned portions 44, which are clearly shown in Figures 7 and 8, and which bear against the spring arms 45.

30 In the form of the invention shown in Figure 9 the same idea is employed as that described in connection with Figures 5 and 6, with, however, the exception that the spacing members 46 or supporting members for the levers 49 are formed integrally with the spring arms 50. This is readily accomplished by striking a tongue 51 outwardly from each spring arm 50, as shown in Figure 9, and using these outwardly struck or 55 outwardly projecting portions 51 as the supporting members for the levers 49.

Figure 10 carries the idea described in connection with Figure 9 one step farther as it eliminates the necessity for forming additional supporting members for the levers 52. Instead each lever 52 is provided with an inwardly turned shoulered portion 53 and with an inwardly projecting tongue or nib 54, which latter in each case passes through an aperture formed in the spring 60 arms 55.

65 It will be seen that with each form of the invention means are provided for causing the spring contact arms of the holder to engage the terminals of the fuse with a very firm pressure 70 and with a face to face contact so that the terminals of the fuse are securely electrically connected to the terminals of the holder in a very simple and efficacious manner.

75 It will also be seen that the fuse is tightly

gripped by the holder and consequently displacement of the fuse in the normal operation thereof is prevented.

It will be seen further that the device is very simple, that it is eminently practical, that it is easy to operate, that it allows the ready positioning or removal of the fuse as the heavy contact pressure is relieved during this operation, but which provides means for applying this heavy 10 or secure contact pressure when the fuse has been positioned.

Although this invention has been described in considerable detail, it is to be understood that such description is intended as illustrative rather 15 than limiting, as the invention may be variously embodied and is to be interpreted as claimed.

We claim:

1. In a device of the class described, a fuse having contact terminals, a pair of clamping jaws 20 for each contact terminal, pressure applying screw means for forcing the jaws of each pair towards each other to tightly clamp the contact terminals of said fuse, and a bail for operating said screw means, said bail when in the released 25 position allowing the easy positioning and removal of said fuse.

2. In a fuse structure, the combination of a fuse having an upper and a lower contact terminal, two pair of clamping jaws for receiving the said 30 contact terminals, one pair of jaws being located above the other pair of jaws to hold said fuse in a substantially upright position, and pressure applying screw means for forcing the jaws into binding engagement with the contact terminals 35 of said fuse, whereby a secure electrical contact

is obtained between said jaws and said contact terminals, the lower pair of said clamping jaws having a supporting member associated therewith to engage the bottom part of the lower terminal of said fuse below the lower pair of clamping jaws and independent of said pressure applying means and of said clamping jaws. 5

3. In a fuse structure, a fuse having terminal contacts, clamping means for engaging said terminal contacts, and two reversely threaded pressure applying means for each clamping means 10 for forcing said clamping means into binding engagement with said terminal contacts, said pressure applying means being distinct and separate from said fuse and being mechanically out 15 of contact with each other.

4. In a fuse structure, a body portion, a pair of spaced insulators, terminal members carried by said insulators, a pair of clamping jaws carried by each terminal member, a fuse having spaced 20 terminal contacts fitting between said jaws, and mechanically distinct screw means for each jaw for forcing said jaws towards each other to tightly bind the terminal contacts of said fuse, said screw means being out of contact with each 25 other.

5. In a fuse structure, a fuse having spaced terminal contacts, clamping means for engaging said terminal contacts, reversely threaded means for forcing said clamping means into binding engagement with said terminal contacts, and a bail 30 for operating said reversely threaded means.
